RAILWAY SWITCH CONTROLLING APPARATUS

Charles A. Brooks, Swissvale, Pa., assignor to The Union Switch & Signal Company, Swissvale, Pa., a corporation of Pennsylvania

Application July 24, 1934, Serial No. 736,665

15 Claims. (Cl. 246—141)

My invention relates to railway switch controlling apparatus of the type wherein a railway track switch is controlled by a manually operable lever and by a traffic controlled contact, and wherein release means is provided for controlling the switch when the traffic controlled contact is opened.

One feature of my invention is the provision of release means for controlling operations of a railway track switch to its normal and reverse positions, irrespective of whether the last previously attempted operation of the switch was completed or not.

I will describe one form of apparatus embodying my invention, and will then point out the novel features thereof in claims.

The accompanying drawing is a diagrammatic view showing one form of apparatus embodying my invention.

Referring to the drawing, the reference characters **1** and **1a** designate the track rails of a stretch of main track **Y** which is divided by insulated joints **2** to form a track section **a—d**. The track section **a—d** is provided with a switch **F** leading into a side track **Z**. Track section **a—d** is provided with a track circuit including a battery **f** connected across the rails adjacent one end of the section, and a track relay designated by the reference character **T** connected across the rails adjacent the opposite end of the section.

The switch **F** is operated by a mechanism **M** which may be of the fluid pressure motor type. Mechanism **M** is controlled by a lock magnet **m** and by normal and reverse magnets **n** and **r** for causing mechanism **M** to operate switch **F** to the normal or reverse positions respectively. Magnets **n** and **r** are controlled by a manually operable lever **V**, a polarized relay **A**, a lock relay **L**, and a manually operable time release **E**. Magnet **m** is controlled by lever **V** and by a polarized switch indication relay **K**.

As shown in the drawing, lever **V** has a normal position **N**, a normal detector lock position **x**, a normal indication lock position **B**, a reverse indication lock position **D**, a reverse detector lock position **y**, and a reverse position **R**. Lever **V** operates various contacts, each of which is closed during a given portion of the movement of lever **V** from either of its extreme positions **N** and **R** to the other. The portion of the movement of lever **V** during which each of the contacts operated by lever **V** is closed is indicated by a reference character adjacent the symbol for the contact, such, for example, as the reference character **Nz** adja-

cent the symbol for contact **N**, which indicates that contact **N** is closed while lever **V** is in its **N** position or in its **x** position or in any other position between these two positions.

Lever **V** is also provided with a latch contact **9** which is operated in a well-known manner by a latch associated with lever **V**. Contact **9** is opened when lever **V** is in its positions **N** or **R** but becomes closed when the leverman starts to move lever **V** between its **N** and **R** positions.

Movement of lever **V** between its **x** and **B** positions is controlled in a well-known manner by a normal lock magnet **NLM** controlling a dog **3** which engages a notched segment **4** rigidly attached to lever **V**. Movement of lever **V** between its **y** and **D** positions is similarly controlled by a reverse lock magnet **RM**.

The time releasing device **E** may be of the well-known manually operable screw type in which the period of operation is not measured but is variable to some extent by the operator or leverman. Operation of such a releasing device, however, enforces an appreciable time delay in connection with operation of other parts of the apparatus. Releasing device **E** is equipped with a normally closed contact **26** which opens at the beginning of each operation of device **E** from its normal position, and which again closes when device **E** is returned to that position. Device **E** also has a contact **6** which is closed at an intermediate point in the operation of device **E** between its normal and reverse positions.

The third contact **27** of device **E** is closed only when device **E** occupies its reverse position. The construction of device **E** is such that there is an enforced time delay between the opening of contact **26** and the closing of contact **6**, and also between the opening of contact **6** and the closing of contact **27** when the device **E** is actuated from its normal to its reverse position. Similar time delays are enforced between the opening of contact **27** and the closing of contact **6**, and between the opening of contact **6** and the closing of contact **26** when the device **E** is actuated from its reverse to its normal position.

Lock relay **L** is normally energized by a circuit which is controlled by track relay **T**, but can also be energized by a circuit controlled by contact **6** of release **E**.

Switch indication relay **K** is of the polarized type, and is so controlled by a pole-changer **P** operated by switch **F** as to be energized by current of normal polarity when switch **F** occupies its normal position, and to be energized by cur-

rent of reverse polarity when switch F occupies its reverse position.

Relay A is also of the polarized type and is so controlled by lever V as to be operated by current of one polarity when lever V is in its position B, and to be operated by current of the reverse polarity when lever V is in its position D. Current of either polarity applied to the windings of relay A is controlled by latch contact 9 and by relay L, and also by either contact 6 of release E or by relay T. Although relay A is illustrated as a polarized relay having two windings in order to economize contacts on lever V, either an ordinary polarized relay having one winding or two neutral relays can be adapted to be controlled by lever V in the D and B positions, to accomplish the same results as are obtained with relay A.

As shown in the drawing, all parts are in a normal condition; that is, lever V and release E are in their normal positions; switch F is in its normal position, and section a—d is unoccupied. With section a—d unoccupied, relay T is energized. With relay T energized, relay L is energized by a circuit passing from terminal b of a suitable source of current not shown in the drawing, through contact 5 of relay T, wire 1, and the winding of relay L, to terminal o of the same source of current. With relay L energized, the normal magnet n is energized by a circuit passing from terminal b, through contact 26 of release E, the front point of contact 28 of relay L, contact 29 of relay A in its right-hand position, contact 30 of lever V, and the winding of magnet n to terminal o. A second circuit for magnet n is also closed, passing from terminal b, through contact 32 of lever V, and the winding of magnet n to terminal o. With switch F in its normal position, pole-changer P is in the position in which current of normal polarity is supplied from terminal b through the winding of relay K to terminal o. Except for latch contact 9, which is open, a circuit would be complete for energizing normal lock magnet NM. Since lever V is not in either its B or its D position, relay A is deenergized. Relay A is, however, of the type in which its polar contacts remain closed in the position corresponding to the last previous direction of energization of its windings, and hence contact 29 is closed in its right-hand position since this relay was last previously energized by current of normal polarity because of lever V having moved through its position B to its position N.

If now, assuming that all parts of the apparatus are in the normal condition as just described, the leverman desires to operate switch F to its reverse position; he will first close latch contact 9, thereby completing a circuit for lock magnet NM, passing from terminal b, through contact 5 of relay T, wire 1, contact 8 of relay L, latch contact 9, wire 10, contact 11 of lever V, wire 11, and the winding of magnet NM to terminal o. Magnet NM, upon becoming energized, raises the associated dog 3 so that it will not engage the upper projection of the associated segment 4, and will therefore permit lever V to be moved to its position D.

With lever V moved to its position D, relay A will be energized by current of reverse polarity in a circuit passing from terminal b, through contact 5 of relay T, wire 1, contact 8 of relay L, latch contact 9, wire 12, contact 24 of lever V, and the right-hand portion of the winding of relay A to terminal o. With relay A energized

by current of reverse polarity, and with lever V in its position D, a circuit is now completed for energizing magnet r, passing from terminal b, through contact 26 of release E, front point of contact 28 of relay L, contact 29 of relay A in its left-hand position, contact 31 of lever V, and the winding of magnet r to terminal o. A circuit is also now completed for energizing lock magnet m, passing from terminal b, through the front point of contact 13 of relay K, contact 18 of lever V, contact 19 of relay K in its left-hand position, wire 25, and the winding of magnet m to terminal o.

With magnets m and r thus energized, mechanism M will move switch F to its reverse position. Switch F, at the beginning of its movement from the normal to the reverse position, opens the contacts of pole-changer P, causing relay K to become deenergized. Contact 13 of relay K therefore opens at its front point, and closes at its back point, thereby completing a second circuit for energizing magnet m, passing from terminal b, through the back point of contact 13 of relay K, wire 25, and the winding of magnet m through terminal o.

Switch F, upon completing its movement to the reverse position, causes pole-changer P to close its contacts in the reverse position, which thereupon causes current of reverse polarity to be supplied to the winding of relay K. With relay K energized in the reverse direction, a circuit will be completed for energizing reverse lock magnet RM, passing from terminal b, through the front point of contact 13 of relay K, contact 18 of lever V, contact 19 of relay K in the right-hand position, contact 20 of lever V, wire 21, and the winding of lock magnet RM to terminal o. Magnet RM, upon becoming energized, lifts the associated dog 3, thereby preventing the engagement of dog 3 with the upper projection of the associated segment 4. The leverman will therefore now complete the movement of lever V from its D position to its R position.

The procedure to be followed and the operation of the apparatus for returning switch F to its normal position under normal conditions by moving lever V from its position R to its position B, is similar to that just described for the operation of the switch to its reverse position, and will therefore be readily understood by reference to the drawing, without further detailed description.

I will next assume that all parts of the apparatus have been returned to their normal condition and that track relay T becomes deenergized, either on account of the presence of the train or for some other reason. If the leverman desires to reverse switch F while track relay T is deenergized, he will attempt to do so by operating release E to its intermediate position, in which its contact 6 becomes closed. On account of relay T being deenergized, the normal energizing circuit for relay L will be open at contact 5 of relay T, but a second circuit for energizing relay L will now be closed, passing from terminal b, through contact 6 of release E, wire 1, and the winding of relay L to terminal o.

If now the leverman closes latch contact 9 preparatory to moving lever V from its x to its D position, a second circuit will be closed for energizing lock magnet NM, which is the same as the circuit previously traced for this magnet, except that it includes contact 6 of release E instead of contact 5 of relay T.

With lock magnet NM energized, the leverman

will move lever V to its D position, thereby completing a second circuit for energizing the reverse winding of relay A, which is the same as the circuit previously traced for this winding except that it includes contact 6 of release E instead of contact 5 of relay T.

The leverman will now continue the operation of release E from its intermediate position to its reverse position in which its contact 27 will become closed, thereby completing a second circuit for energizing magnet r, which is the same as the circuit previously traced from magnet r except that it includes contact 27 of release E, and the back point of contact 28 of relay L, instead of contact 26 of release E and the front point of contact 28 of relay L. Magnet m will now be energized by the circuit previously traced. With magnets m and r energized, mechanism M will move switch F to its reverse position as previously described, causing relay K to again become energized in the reverse direction. With relay K energized in the reverse direction, magnet RM will become energized by the circuit previously traced, and hence the leverman can complete the movement of lever V to its R position.

If, for some reason, switch F should have moved only part way from its normal to its reverse position, pole-changer P would not become closed in its reverse position, and hence relay K would remain deenergized. With relay K deenergized, magnet RM would also remain deenergized, and hence the leverman could not complete the movement of lever V to its reverse position R. With apparatus embodying my invention, the leverman can now move the switch back and forth from its normal position to the obstructed position in an attempt to remove the obstruction. For each such movement of the switch back and forth while relay T remains deenergized, the leverman must return release E to its intermediate position to close contact 6, and then return it to its reverse position to close contact 27. Such operation of release E enforces a time delay for each such operation of switch F.

Assuming that the switch has failed to complete its movement to its reverse position and that the leverman desires to return the switch to its normal position, he will return lever V to its position B and will return release E to its intermediate position, thereby closing contact 6 for energizing relay L. With relay L energized, a circuit will be completed for energizing the normal winding of relay A which is the same as the circuit previously traced for the reverse winding of this relay through contact 6 of release E as far as wire 22, and then passing through contact 23 of lever V and the normal winding of relay A to terminal o.

The leverman will now return release E to its reverse position for closing contact 27. A circuit will thereby be completed for energizing the normal control magnet n, passing from terminal b, through contact 27 of release E, back point of contact 28 of relay L, contact 29 of relay A in its right-hand position, contact 30 of lever V, and the winding of magnet n to terminal o. Since relay K is still deenergized on account of switch F not having completed its operation to the reverse position, magnet m will be energized by its circuit previously traced through the back point of contact 13 of relay K.

With magnets n and m energized, switch F will be returned to its normal position by mechanism M. With switch F again in its normal position, pole-changer P will be in its normal position, and hence relay K will again be energized by current

of normal polarity. With relay K energized by current of normal polarity, a third circuit will be completed for energizing lock magnet NM, passing from terminal b, through the front point of contact 13 of relay K, contact 14 of lever V, contact 15 of relay K in its left-hand position, contact 16 of lever V, wire 17, and the winding of magnet NM to terminal o.

With magnet NM energized, the leverman can continue the movement of lever V from its B to its N position if he so desires. He may desire to do this in order to permit a signal to be cleared for governing traffic movements over switch F in its normal position.

If, however, he desires to again attempt to reverse switch F, he will now again return release E to its intermediate position, this operation requiring a time delay. With release E in its intermediate position, contact 6 will again be closed and the procedure will then be as previously described for the former attempt to move switch F to its reverse position under the control of release E.

It will be apparent from the foregoing description that the apparatus shown in the accompanying drawing permits the operator to move switch F under emergency conditions in either direction during any part of its stroke. It is also apparent that for each such emergency operation of the switch, release E enforces a time delay in order to protect against the possibility of a train derailment.

Although I have herein shown and described only one form of railway switch controlling apparatus embodying my invention, it is understood that various changes and modifications may be made therein within the scope of the appended claims, without departing from the spirit and scope of my invention.

Having thus described my invention, what I claim is:

1. In combination with a railway switch having a normal and a reverse position, a manually operable lever movable between a normal and a reverse position, a normal contact controlled by said lever which becomes closed when the lever is moved near to its normal position and remains closed thereafter until the lever is moved near to its reverse position, a reverse contact controlled by said lever which becomes closed when the lever is moved near to its reverse position and remains closed thereafter until the lever is moved near to its normal position; a manually operable time releasing device having a normally closed back contact which opens when said device is actuated from its normal position, a normally open middle contact which becomes closed for a brief interval during actuation of said device following the opening of said back contact, and a normally open front contact which becomes closed after the expiration of a time interval during said actuation subsequent to the opening of said middle contact; a lock relay, means governed by traffic conditions for energizing said relay, means including a first front contact of said relay for preventing movement of said lever from the normal or from the reverse position; means for moving said switch from the normal to the reverse position under normal conditions including the back contact of said device, a second front contact of said relay, and said reverse contact, effective when said lever is moved from its normal near to its reverse position; means for moving the switch from the reverse to the normal position under normal conditions including said back contact, 70

- said second front contact, and said normal contact, effective when said lever is moved from its reverse near to its normal position; means controlled by said middle contact for energizing said 5 relay under emergency conditions; means for moving said switch from the normal to the reverse position under emergency conditions including the front contact of said device, a back contact of said relay, and said reverse contact, 10 effective when said lever is moved from its normal near to its reverse position; and means for moving said switch from the reverse to the normal position under emergency conditions including said front contact of the device, said back contact 15 of the relay and said normal contact, effective when said lever is moved from its reverse near to its normal position.
2. In combination with a railway switch having a normal and a reverse position, a manually 20 operable lever movable between a normal and a reverse position, a time releasing device having a middle contact which becomes closed for a brief interval upon actuation of said device and a front contact which becomes closed at the expiration 25 of a time interval following the opening of said middle contact; a first contact which becomes closed when the lever is moved from its reverse near to its normal position provided said middle contact is closed, said first contact remaining 30 closed thereafter until the lever is moved near to its reverse position; a second contact which becomes closed when the lever is moved from its normal near to its reverse position provided said middle contact is closed, said second contact re- 35 maining closed thereafter until the lever is moved near to its normal position; means controlled by said lever and including said second contact as well as said front contact for moving said switch to the reverse position, and means controlled by 40 said lever and including said first contact as well as said front contact for moving said switch to the normal position.
3. In combination with a railway switch having a normal and a reverse position, a manually 45 operable lever having N, B, D and R positions, a lock relay, a first contact controlled by said lever and by said relay which becomes closed when the lever is moved to its B position provided said relay is energized and remains closed thereafter until the lever is moved to its D position, a second 50 contact also controlled by said lever and by said relay which becomes closed when the lever is moved to its D position provided said relay is energized and remains closed thereafter until the lever is moved to its B position, a manually 55 operable time releasing device having a middle contact which becomes closed for a brief period after a time interval during actuation of said device and a front contact which becomes closed after the expiration of an additional time interval following the opening of said middle contact, means controlled by said relay when said relay is deenergized for preventing movement of the 60 lever from its N or its R position, means controlled by said middle contact for energizing said relay, means controlled by the front contact of said device and by said second contact effective when said relay is deenergized and said lever is moved to its D position for moving said switch to the reverse position, and means controlled by the front contact of said device and by said first contact effective when said relay is deenergized and said lever is moved to the B position for moving said switch to the normal position.
4. In combination with a railway switch hav- 75 ing a normal and a reverse position, a manually operable lever having N, B, D and R positions, a manually operable time releasing device which assumes a first position upon the expiration of a first time interval during actuation and which subsequently assumes a second position upon the expiration of an additional time interval, means controlled by said device for at times preventing movement of the lever from its N or its R position unless said device occupies said first position, a first contact which becomes closed when said device occupies said first position and the lever is moved to its B position remaining closed thereafter until the lever is subsequently moved to the D position, a second contact which becomes closed when said device occupies said first position and the lever is moved to its D position remaining closed thereafter until the lever is subsequently moved to the B position, means controlled by said second contact effective when said device occupies said second position and the lever is moved to its D position for moving said switch to the reverse position, and means controlled by said first contact effective when said device occupies said second position and the lever is moved to its B position for moving said switch to the normal position.
5. In combination, a stretch of railway track including a switch, a manually operable lever having a first and a second position, a first contact controlled by said lever which becomes closed when said lever is moved to its first position and which then remains closed until said lever is moved to its second position, a second contact controlled by said lever which becomes closed when said lever is moved to its second position and which then remains closed until said lever is moved to its first position, a traffic contact responsive to traffic on said track adjacent said switch so that said contact is closed when said stretch of track is unoccupied adjacent said switch and said contact opens when a train approaches said switch, a manually operable time release having a normally closed contact which opens as soon as operation of said release is begun and a middle contact which closes after an interval in the operation of said release and which then opens as operation of said release is continued as well as a reverse contact which closes after a further interval during the operation of said release, means controlled by said normally closed contact and by said first and second contacts for controlling operations of said switch to its normal and reverse positions while said traffic contact is closed, means controlled by said traffic contact for at times preventing operation of said first and second contacts while said traffic contact is open, means controlled by said middle contact for permitting operation of said first and second contacts while said traffic contact is open, and means controlled by said reverse contact and by said first and second contacts for controlling operations of said switch to its normal and reverse positions respectively while said traffic contact is open.
6. In combination, a stretch of railway track including a switch, a manually operable lever having a first and a second position, a polarized relay, a polar contact of said relay having a normal and a reverse position and which when 70 said relay becomes deenergized remains closed in the position corresponding to the last previous direction of energization of said relay, a manually operable release having a normal position and a middle position and also a reverse posi- 75

- tion, means controlled by said release in its middle position or by the unoccupied condition of said stretch adjacent said switch as well as by said lever in its first or its second position for controlling said polarized relay, means controlled by said release in its normal position and by said polarized relay and also by said lever for controlling operation of said switch to its normal or its reverse position when there is no traffic on said stretch adjacent said switch, and means controlled by said release in its reverse position and by said polarized relay for controlling operation of said switch to its normal or its reverse position when said stretch of track is occupied by a train adjacent said switch. 5
7. In combination, a stretch of railway track including a switch, a manually controllable lever having a first and a second position, a manually controllable time release having a normal position and a middle position and also a reverse position, means controlled by said time release in its normal position and by said lever for controlling operations of said switch when said stretch of track is unoccupied adjacent said switch, a first contact controlled by said time release in its middle position and by said lever in its first position, a second contact controlled by said time release in its middle position and by said lever in its second position, and means controlled by said time release in its reverse position and by said first and second contacts for controlling operations of said switch to its normal and reverse positions if said lever is operated to its first and second positions respectively while said stretch of track is occupied adjacent said switch. 10
8. In combination, a stretch of railway track including a switch, a manually controllable lever having a first and a second position, a manually controllable time release having a normal position and a middle position and also a reverse position, means controlled by said time release in its normal position and by said lever for controlling operations of said switch when said stretch of track is unoccupied adjacent said switch, a first contact which closes in response to the closing of a circuit controlled by said time release in its middle position and by said lever in its first position said first contact then remaining closed until said lever is moved to its second position, a second contact which closes in response to the closing of a circuit controlled by said time release in its middle position and by said lever in its second position said second contact then remaining closed until said lever is moved to its first position, and means controlled by said time release in its reverse position and by said first and second contacts for controlling operations of said switch to its normal and reverse positions when said lever is operated to its first and second positions respectively while said stretch of track is occupied adjacent said switch. 15
9. In combination, a stretch of railway track including a switch, a manually controllable lever having a first and a second position, a manually controllable time release having a normal position and a middle position and also a reverse position, means controlled by said time release in its normal position and by said lever for controlling operations of said switch when said stretch of track is unoccupied adjacent said switch, a polarized relay, means controlled by said time release in its middle position and by said lever in its first and second positions for energizing said polarized relay in normal and reverse directions, and means controlled by said time release in its reverse position and by said polarized relay for controlling operations of said switch to its normal and reverse positions irrespective of whether the last previously attempted operation of said switch was completed or not. 20
10. In combination, a stretch of railway track including a switch, a manually controllable lever having a first and a second position, a manually controllable time release having a first and a second position, means including said lever for controlling operations of said switch when said stretch of track is unoccupied adjacent said switch, a first contact controlled by said time release in its first position and by said lever in its first position, a second contact controlled by said time release in its first position and by said lever in its second position, and means controlled by said time release in its second position and by said first and second contacts for controlling operations of said switch to its normal and reverse positions if said lever is operated to its first and second positions respectively while said stretch of track is occupied adjacent said switch. 25
11. In combination, a stretch of railway track including a switch, a manually controllable lever having a first and a second position, a manually controllable time release having a first and a second position, means including said lever for controlling operations of said switch when said stretch of track is unoccupied adjacent said switch, a first contact controlled by said time release in its first position and by said lever in its first position, a second contact controlled by said time release in its first position and by said lever in its second position, and means controlled by said time release in its second position and by said first and second contacts for controlling operations of said switch to its normal and reverse positions irrespective of whether the last previously attempted operation of said switch was completed or not. 30
12. In combination, a stretch of railway track including a switch, a manually controllable lever having a first and a second position, a manually controllable time release having a normal position and a first and a second reverse position, means including said time release in its normal position and said lever for controlling operations of said switch when said stretch of track is unoccupied adjacent said switch, a polarized relay, means controlled by said time release in its first reverse position and by said lever in its first and second positions for energizing said polarized relay in the normal and reverse directions, and means controlled by said time release in its second reverse position and by said polarized relay for controlling operations of said switch to its normal and reverse positions irrespective of whether the last previously attempted operation of said switch was completed or not. 35
13. Apparatus for the control of a movable device comprising a two-position control lever and a two-position storing relay adapted to remain in its last-operated position when deenergized, a locking relay energized only when conditions are favorable for the operation of the device, means effective when the locking relay is energized and the lever is moved from one position to the other to operate the storing relay to a corresponding position, and a control circuit closed only when the locking relay is energized for operating the device to a position corresponding to that of said storing relay. 40

14. Apparatus for the control of a movable device comprising a control member and a storing relay each having a normal and a reverse position, a locking relay responsive to conditions adjacent the device, means controlled by the locking relay and effective when the member is moved from one position to the other to operate the storing relay to a position corresponding to that to which the member is moved provided conditions adjacent the device are favorable for operation of the device, and means for operating the device comprising a circuit including, in series, corresponding contacts of the member and of the storing relay and also a contact closed by the locking relay if conditions adjacent the device are favorable for operation of the device.
15. Apparatus for the control of a movable device comprising a control member and a storing relay each having a normal and a reverse position, a locking relay energized only when conditions are favorable for operation of the device, means effective when the member is moved from one position to the other to operate the storing relay to a position corresponding to that to which the member is moved provided the locking relay is then energized, and a control circuit for operating the device closed only when the member and the storing relay occupy corresponding positions and only while said locking relay is energized.

CHARLES A. BROOKS. 15
